TREATING HYDROCARBON OILS

Addison S. Bailey, Houston, Tex., and Edward M. Reynolds, Tulsa, Okla., assignors to The Texas Company, New York, N. Y., a corporation of Delaware

Application February 12, 1929. Serial No. 339,300

13 Claims. (Cl. 196—49)

This invention relates generally to the conversion of higher boiling hydrocarbons into lower boiling ones and has particular reference to certain improvements in the treatment of liquid oil or residue developed in the cracking reaction.

It has been sought to utilize the heat contained in residual or liquid oil as withdrawn from a cracking chamber to effect the distillation thereof, for the purpose of recovering therefrom gasoline or naphtha distillates as well as heavier distillates, by directing the oil withdrawn from the cracking chamber into an expansion chamber or still operating at reduced pressure to effect the distillation. One of the chief difficulties experienced in such procedure is that when the discharge of residue from the cracking still into the tar distilling chamber is effected by taking shots in a customary manner the residue distilling chamber is necessarily subjected to great fluctuations in pressure which disturbs the conditions of distillation therein. It is desirable to maintain the residue distilling chamber at substantially a uniform pressure throughout the distillation in order that the products obtained in the distillation may be constantly kept at the tests desired. The operation in the residue distilling chamber may be smoothed out somewhat when a single residue stripping unit is operated in conjunction with a plurality of batteries of pressure stills by timing the taking of shots from the several batteries and the same result can be obtained, although to a more limited extent, when a single battery composed of a plurality of stills is used by properly timing the shots taken from the several stills, but even these procedures do not accomplish that even distillation in the distilling chamber which is desirable.

In accordance with my invention a surge drum or chamber is provided between the cracking chamber and the residue distilling chamber and the liquid oil is withdrawn from the cracking chamber into the surge drum where a certain amount of expansion is allowed to take place. The surge drum operates to cushion the shock of the shots from the cracking chamber and thus permit the liquid to be discharged in a regulated manner into a distilling chamber wherein approximately constant conditions may be thus maintained.

In order to more fully disclose my invention reference will now be had to the accompanying drawing which illustrates a preferred embodiment of the invention wherein:

Figure 1 is a diagrammatic sectional elevation of an apparatus constructed in accordance with

the invention and constituting an embodiment thereof.

Figure 2 is an enlarged section taken on the line 2—2 of Figure 1.

In the apparatus thus illustrated a so-called coil and drum or tube and tank type of cracking system is shown but it is to be understood that the invention may well be practiced in connection with other types of cracking processes. The cracking apparatus includes a heating coil 10 and a cracking still 11 with a charging line 13 and pump 14 adapted for introducing a suitable charging stock to the heating coil and with a transfer line 15 for conducting the heated oil from the coil 10 to the still 11. The heating coil 10 is shown disposed in a furnace 16 which is intended to supply sufficient heat so that the oil may preferably be brought to a cracking temperature before it leaves the coil. The still 11 may either be heated in a furnace or insulated to prevent or retard loss of heat. If desired a plurality of stills may be employed in lieu of the single still shown. A vapor line 17 serves to conduct vapors from the still to a dephlegmator or fractionating column 18 which may be in the form of a bubble tower or a packed tower or of any other suitable design. A vapor line 19 conducts the overhead vapor fraction to a condenser 20 and a receiving drum 21 preferably having a valved gas outlet 22 and a valved condensate outlet 23 is provided for collecting the distillate. A line 24 is shown extending to a hot oil pump 25 having a discharge line 26 so that reflux condensate from the fractionating column 18 may be forced into the coil 10.

A tar or residue draw-off line 27 is shown extending to a tar main 28 to which are also connected a plurality of lines as 27a, 27b, etc., each of which may extend to a separate battery or cracking unit (not shown). The tar main 28 is equipped with a pressure reducing valve 29 and extends to a surge drum 30. A line 31 is provided for conducting the oil from the surge drum 30 to a distilling chamber 32. As clearly shown in Figure 2 a preferred method of construction is to arrange the connections 29 and 31 with the chamber 30 tangentially of the chamber. With such construction a more or less rotary motion may be imparted to the material in the surge chamber that may tend to settle out coke and carbon therein. A line 33 is shown near the bottom of the chamber so that if desired drags may be taken on the chamber 30 at intervals for the purpose of preventing the chamber from becoming choked up with accumulated coke. The

line 33 may extend to suitable tankage; ordinarily it is not best to connect this line to the distilling chamber 32. A manhead 34 is preferably provided at the bottom of the surge chamber for the purpose of inspection and cleaning at the end of a run. It is preferable to have a certain amount of space in the chamber 30 above the outlet line 31 in which space compressible vapors and gases may accumulate which may facilitate the cushioning operation.

The distilling chamber 32 may be of any suitable construction but in the preferred construction shown the line 31 enters at the upper end of the chamber and thus operates to direct the material from the surge drum over a spreader or hood 35 beneath which are a plurality of baffles 62 to spread or film the descending liquid in order to thereby facilitate its vaporization. A steam line 36 is shown in the lower portion of the distilling chamber for the purpose of supplying live steam, either saturated or superheated, to the chamber, although it may be stated that in many cases no steam or other carrier gas or other heating means may be employed, the heat contained in the residue being adequate to effect the desired distillation. The vapor line shown in the drawing includes an elbow 37, positioned underneath the spreader or hood 35, connected to a pipe 38. The flow of oil from the surge drum 30 to the distilling chamber 32 may be controlled by a valve 39 in the line 31 which valve may be controlled manually or by suitable automatic means. In the drawing a by-pass line 40 is shown having a valve 41 controlled by a float 42 positioned in the distilling chamber 32 so that the delivery of oil from the surge chamber to the distilling chamber may thus be controlled by the liquid level in the distilling chamber. If desired, the flow of material through the line 31 from the surge drum to the distilling chamber may be controlled by an automatic valve (not shown) operated by the comparatively slight fluctuations in pressure which may occur in the distilling chamber. A line 43 is provided for withdrawing the stripped residue from the chamber 32.

Two dephlegmators or fractionating columns 44 and 45 are shown in the drawing for the tar or residue stripping unit with the vapor line 38 extending from the still 32 to the tower 44 and with a vapor line 46 extending from the tower 44 to the tower 45. The towers 44 and 45 may be in the form of bubble towers or packed towers or in the form of any suitable dephlegmating or fractionating apparatus. Steam lines 47 and 48 are shown near the bottoms of the two towers 44 and 45, respectively, for the purpose of introducing live steam into the towers to aid the distillation therein. Two towers are indicated for the purpose of obtaining two cuts of heavy condensate but if it is desired to obtain a greater number of cuts or only a single cut of heavy condensate the fractionating equipment may be altered accordingly.

Valved draw-off lines 49 and 50 extend from the towers 44 and 45, respectively, to a common condensate line 51 which extends to a pump 52 having a discharge line 53 extending to the heating coil 10 so that either one or both of the reflux condensates withdrawn from the towers 44 and 45 may be pumped directly to the heating coil 10. It is preferable to cycle back these condensates in a heated condition as withdrawn from the towers and it may be observed that both the reflux condensate obtained from the tar stripper which is admitted to the coil 10 through the

line 53 and the reflux condensate from the fractionating column 18 which is admitted through the line 26 are preferably introduced into the heating coil at points therein at which the oil charge in the coil is at substantially the temperature of the reflux condensates introduced. Branch lines 54 and 55 are shown connected to the lines 49 and 50, respectively, so that if desired either or both of the reflux condensates withdrawn from the towers 44 and 45 may be conducted to tankage.

A vapor line 56 is provided for conducting the overhead vapor fraction from the tower 45 to a condenser coil 57. The outlet of the coil 57 terminates in a trap 58 for trapping out water from the condensate. If steam is not used in the towers 44 and 45 this trap may be omitted. A receiver 59 is shown for collecting the final light distillate.

In practicing the invention with the apparatus thus illustrated a suitable charging stock, such as for example gas oil or a crude residuum, is charged to the heating coil 10 and passed thence into the still 11. Any suitable cracking temperatures and pressures may be employed. However, in a preferred example of the invention conversion temperatures of the order of 750° F. to 900° F. may be maintained in the still 11 under pressures of the order of 200 to 600 pounds. The evolved vapors are fractionated in the column 18 from which reflux condensate is withdrawn and conducted to the heating coil 10 while the overhead vapor fraction is condensed in the condenser 20 and collected as a gasoline or naphtha distillate in the receiver 21. Tar or residue is withdrawn through the line 27 to the tar header 28 and passed thence through the pressure regulating valve 29 to the surge drum 30 and thence into the distilling chamber 32 as has heretofore been explained.

Normally the surge drum 30 may be subjected to considerable variations in pressure dependent upon the frequency and extent of the drags or shots taken from the still 11 as well as from the other batteries to which the lines 27a, 27b, etc. are connected, in cases where it is desired to operate the tar stripping equipment in conjunction with a plurality of batteries. In general, however, the pressure obtaining in the drum 30 will be materially lower than that obtaining in the still 11 and will be higher than that of the distilling chamber 32. It is preferable to operate the distilling chamber under a pressure approximating or approaching atmospheric. If desired, a slight superatmospheric pressure, such for example as 5 to 10 pounds, may be employed in the distilling chamber 32 which pressure facilitates the discharge of products from the chamber. Pumps may be employed in withdrawing the stripped liquid from the distilling chamber 32 as well as for withdrawing the reflux condensates from the towers 44 and 45 and the final distillate from the receiver 59. For most purposes it is unnecessary to employ a vacuum in the residue distilling operation although the use of a vacuum is not precluded in the practice of the invention. It will be thus seen that the pressure differentials between the still 11, the surge drum 30 and the distilling chamber 32 will vary within comparatively wide limits.

As a typical example of the invention, however, it may be stated that a suitable cracking operation may be carried on at a pressure of about 400 pounds in the still 11, with the pressure in the surge drum 30 fluctuating between about 275 to 50 pounds and

with approximately 10 to 15 pounds pressure in the still 32.

Although as has been stated, automatic means may be employed in controlling the delivery of liquid from the surge chamber 30 to the distilling chamber 32, such automatic means is ordinarily unnecessary, since proper control may be accomplished by manual manipulation of the valve 39. If desired, instead of withdrawing residue from the cracking stills by intermittent shots or drags the residue may be withdrawn in a substantially continuous manner and thus directed into the surge drum 30.

In carrying out the process it is preferable, although not necessary, to carry on the fractionation of the vapors obtained in the tar stripping operation to such an extent as to obtain a naphtha or gasoline distillate in the receiver 59 of substantially the same boiling point as that of the pressure distillate collected in the receiver 21. It is likewise advantageous to employ the two towers 44 and 45 to thus make two cuts of gas oil, the heavier of which may well be returned to the same cracking system from which it was derived while the lighter cut may be otherwise disposed of as by being subjected to cracking at higher temperatures and pressures than that of the cracking system from which it was derived.

Although the invention has been described specifically as applied to the treatment of residues obtained from cracking stills wherein distillation takes place during the cracking reaction the invention may also be applied to processes in which the oil is subjected to cracking without concomitant separation and removal of vapor from the cracking chamber, the converted oil or synthetic crude, as it has sometimes been termed, being withdrawn from a high pressure reaction chamber, such for example as one operated under from 600 to 800 pounds pressure, and then discharged into the surge drum and delivered thence in a regulated quantity into the distilling chamber.

Although the surge drum operation herein set forth is most useful in cases where the removal of pressure tar from the cracking stills is carried on intermittently by taking periodic shots or drags from the stills it may also be employed to advantage in cases where the withdrawal of residue is continuous.

Obviously many modifications and variations of the invention, as hereinbefore set forth, may be made without departing from the spirit and scope thereof, and therefore, only such limitations should be imposed as are indicated in the appended claims.

I claim:

1. In a process of distillation in a reduced pressure distilling zone of the hot residue taken from a superatmospheric pressure conversion zone, the process that comprises first introducing the residue into a surge chamber interposed between the superatmospheric pressure conversion zone and the reduced pressure distilling zone, maintaining said chamber at a range of pressures materially below said conversion zone pressure without distilling off a distillate from said chamber, distilling the hot residue under the reduced pressure, not materially affected by variations that may occur in the discharge of material from said conversion zone, in the distilling zone by means of its own contained heat, separating the oil charged into said reduced pressure distilling zone into fractions comprising a fuel oil, a plurality of gas oils, and a naphtha, and returning one of said

gas oil fractions to the pressure conversion zone.

2. In a process for converting higher boiling hydrocarbons into lower boiling ones by the application of heat and pressure the steps comprising passing a developed residue intermittently into a lower pressure zone wherein pressure variations may take place without the separate removal of vapor, passing all products therefrom in a regulated continuous stream into a flash chamber maintained under a substantially constant and still further reduced pressure and passing a resulting overhead vapor to a dephlegmating zone while withdrawing a relatively heavy residue.

3. In the conversion of higher boiling hydrocarbons into lower boiling ones by the application of heat and pressure, the process that comprises intermittently passing a residue developed in the conversion into a lower pressure zone wherein pressure variations may take place without the separate removal of vapor, passing products therefrom in a regulated continuous stream into a flash chamber maintained under a substantially constant and still further reduced pressure, passing a resulting overhead vapor to a dephlegmating zone, withdrawing a relatively heavy liquid residue from said flash chamber, passing the lighter vaporous constituents from said dephlegmating zone to a further dephlegmating zone while condensing a relatively heavy fraction in said first dephlegmating zone, and delivering a final vapor from said second dephlegmating zone to a condenser to form a desired ultimate distillate while condensing in said zone a fraction lighter than the fraction condensed in the first dephlegmating zone but heavier than the ultimate distillate.

4. In the treatment of hydrocarbon oils wherein the oil is subjected to cracking in a reaction chamber under superatmospheric pressure and wherein products are withdrawn from the reaction chamber and subjected to distillation in a distilling apparatus maintained under a lower pressure than that of the reaction chamber to effect a separation of said products into distillate and residue, the process that comprises delivering the withdrawn products, prior to said distillation, into an expansion chamber from which no separate vapor fraction is withdrawn and which is maintained under a range of pressures materially below that of the reaction chamber and passing a regulated quantity of said products thence to the distilling apparatus which is operated so as not to be materially affected by any variations that may occur in the discharge of material from said reaction chamber.

5. In the treatment of hydrocarbon oils wherein the oil is subjected to cracking in a reaction chamber under superatmospheric pressure and wherein products are withdrawn from the reaction chamber and subjected to auto-distillation in a distilling apparatus maintained under a lower pressure than that of the reaction chamber to effect separation of said products into distillate and residue, the process that comprises delivering the withdrawn products, prior to said distillation, into an expansion chamber from which no separate vapor fraction is withdrawn and which is maintained under a range of pressures materially below that of the reaction chamber and passing a continuous stream of products, with contained heat sufficient to effect distillation, thence to the distilling apparatus.

6. In the treatment of hydrocarbon oils wherein the oil is subjected to cracking in a reaction

- chamber under superatmospheric pressure and wherein products are withdrawn from the reaction chamber and subjected to subsequent auto-distillation in a distilling apparatus maintained under a lower pressure than that of the reaction chamber, the step that comprises delivering the withdrawn products into an accumulating chamber wherein without distilling off a distillate a quantity of the oil is accumulated under a range of pressures materially below that of the reaction chamber and under conditions such that the density of the products in the accumulating chamber may vary, dependent on the influx of material from the cracking chamber, delivering a regulated stream of material to the distilling apparatus and carrying out the distillation in a controlled manner not materially affected by any variations that may occur in the discharge of material from the cracking chamber.
7. In the treatment of hydrocarbon oils wherein in the oil is subjected to cracking and distillation under superatmospheric pressure in a cracking still, the process that comprises withdrawing residue from the cracking still and expanding it into a chamber maintained under a materially lower pressure without distilling off a distillate and passing the expanded oil into a distilling chamber maintained under a still lower pressure wherein distillation to effect a stripping of said residue takes place said distillation being not materially affected by any variations that may occur in the discharge of material from said cracking still.
8. In the treatment of hydrocarbon oils wherein in the oil is subjected to cracking and distillation under superatmospheric pressure in a cracking still, the process that comprises delivering residue from the cracking still in shots to a surge chamber maintained at lower pressures than that of the cracking still, passing products substantially continuously from the surge chamber to a distilling chamber maintained at lower pressure than that of the surge chamber and wherein distillation occurs without distilling off a distillate from the surge chamber, permitting fluctuation of pressure to take place therein with consequent compression and expansion of contained products, dependent on the influx of material from the cracking still, to thereby largely absorb the effect of the intermittent delivery of material to the surge chamber and promote an even distillation in the distilling chamber.
9. The process of treating hydrocarbon oils that comprises subjecting hydrocarbon oil in a plurality of separate bodies to cracking under superatmospheric pressure, withdrawing oil from the several bodies of oil undergoing cracking and delivering the withdrawn oil into a common accumulating drum in which fluctuations of pressure and consequent compression and expansion of contained products, dependent on the influx of material from the several bodies of oil, are permitted to take place without distilling off a distillate, and continuously passing oil from the accumulating drum to a distilling apparatus in which the oil is subjected to distillation at lower pressure than that of the accumulating drum.
10. The method of treating residue from a pressure cracking still which comprises intermittently delivering residue from the pressure still to a surge chamber maintained under a lower pressure than that of said pressure still and wherein coke is permitted to settle out and the effect of the intermittent delivery of residue is absorbed or cushioned without distilling off a distillate, passing a substantially continuous stream of settled oil from the surge chamber to a distilling chamber where distillation takes place under a further reduced pressure and periodically withdrawing additional oil from the surge chamber from near the bottom to effect removal of accumulated coke therefrom.
11. In the treatment of hydrocarbon oils wherein in the oil is subjected to cracking in a reaction chamber under superatmospheric pressure and wherein products are withdrawn from the reaction chamber and subjected to auto-distillation in a distilling apparatus maintained under lower pressure than that of the reaction chamber, the process that comprises delivering the withdrawn products, prior to said distillation, into an expansion chamber from which no separate vapor fraction is withdrawn and which is maintained under a range of pressures materially below that of the reaction chamber and distilling apparatus, passing a regulated quantity of oil with contained heat sufficient to effect distillation, from said expansion chamber to the lower pressure distilling apparatus which is so operated as not to be materially affected by any variations that may occur in the discharge of material from said reaction chamber, subjecting resultant vapors to fractionation to form a condensate and conducting said condensate to the reaction chamber.
12. A process for the cracking and flash distillation of hydrocarbon oils that comprises subjecting hydrocarbon oil to cracking in a reaction chamber under superatmospheric pressure, withdrawing products from the reaction chamber and passing them into a surge chamber from which no separate vapor fraction is withdrawn, maintaining said surge chamber under a range of pressures materially below that of the reaction chamber and permitting the pressures in the surge chamber to fluctuate within a range of several hundred pounds, passing a regulated quantity of oil with contained heat sufficient to effect distillation from said surge chamber to an auto-distilling apparatus and subjecting the oil to distillation therein under a low substantially constant pressure approaching atmospheric.
13. A process for the cracking and flash distillation of hydrocarbon oils that comprises subjecting hydrocarbon oil to cracking in a reaction chamber under superatmospheric pressure of the order of 400 pounds, withdrawing products from the reaction chamber and passing them into a surge chamber from which no separate vapor fraction is withdrawn, maintaining said surge chamber under a range of pressures materially below that of the reaction chamber and permitting the pressures in the surge chamber to fluctuate within a range of the order of 275 pounds to 50 pounds, passing a regulated quantity of oil with contained heat sufficient to effect distillation from said surge chamber to an auto-distilling apparatus and subjecting the oil to distillation therein under a low superatmospheric pressure of the order of 10 to 15 pounds.

ADDISON S. BAILEY.
EDWARD M. REYNOLDS.
